UNITED STATES PATENT OFFICE

EDWARD H. BOICOURT AND ALLAN H. BOICOURT, OF ROCKWELL CITY, IOWA

AUTOMATIC FUSE SETTING APPARATUS

Application filed January 6, 1930. Serial No. 418,859.

The present invention relates to an apparatus for use in electrical circuits whereby after one fuse has been blown out another fuse will be substituted in circuit therefor in 5 an automatic manner.

Another very important object of the invention resides in the provision of an apparatus of this nature wherein a predetermined time interval is allowed before a fuse is substituted in the circuit for a blown out fuse to give the circuit an opportunity of being unloaded.

A still further very important object of the invention resides in the provision of an 15 apparatus of this nature which is exceedingly simple in its construction, inexpensive to manufacture, strong and durable, compact and convenient in its arrangement of parts, thoroughly efficient and reliable in use and 20 operation, and otherwise well adapted to the purpose for which it is designed.

With the above and numerous other objects in view as will appear as the description proceeds, the invention resides in certain 25 novel features of construction, and in the combination and arrangement of parts as will be hereinafter more fully described and claimed.

In the drawings:

20 Figure 1 is a front elevation of the apparatus embodying the features of our invention,

Figure 2 is a vertical section therethrough taken substantially on the line 2—2 of Figure 1,

Figure 3 is a vertical section taken substantially on the line 3—3 of Figure 2,

Figure 4 is a horizontal section taken substantially on the line 4—4 of Figure 2,

Figure 5 is a perspective view of one of the fuses,

Figure 6 is a perspective view of a pair of hinge sections,

Figure 7 is a perspective view of the lower end of one of the slide bars,

Figure 8 is a detail section taken substantially on the line 8—8 of Figure 3,

Figure 9 is a detail sectional view through one of the switch elements.

50 Referring to the drawings in detail it will

be seen that the numeral 5 denotes a casing the front of which is open, being closable by a panel 6. Depending from the sides of the panel 6 are leaf bars 7 with pins 8 to be received in bayonet slots 9 in leaf bars 10 depending from the side walls of the casing 5 thereby allowing the panel 6 to swing to open and closed positions and when in open position allowing the same to be readily removed as will be quite apparent.

Four pairs of guide rollers 11 are mounted on the inner side of the panel 6 to receive slide bars 12 to permit vertical movement thereof. Blocks 14 are mounted on the upper end of the slide bars 12 and have vertical racks 15 thereon. Bracket plates 16 are mounted on the panel and have journaled therein a shaft 17 with rack pinions 18 on the ends thereof disposed below the bottom teeth of the racks 15 when the slides 12 are in uppermost 70 position.

A gear 19 is mounted on the center of the shaft 17 and is operatively connected with a suitable mechanism. The escapement mechanism illustrated in the drawings includes a 75 shaft 20 journaled through the plates 16 having a fly wheel 21 at one end and a plate 22 at the other end formed with lateral ears 23 through which is slid able rod 24 having stops 25 and 26 thereon and a weight 27 slid able 80 thereon between the stops 25 and 26.

A pivoted stop 28 is mounted on one of the bracket plates and is held in a normal position by means of a spring 29. When the shaft 20 is rotating the centrifugal force causes 85 the weight 27 to abut the stop 25 to project the rod 24 so as to engage the stop 28 thereby stopping the rotation of the shaft 20 until the weight falls down to slide the rod 24 downwardly out of the way of the stop 28 90 and further rotation of the shaft 20 is permitted.

Thus the shaft 20 when properly actuated as will be described hereinafter has an intermittent motion similar to that found in most 95 escapement mechanisms.

A plurality of fuses are mounted in the apparatus, each fuse including a tube 30 of insulating material having at one end operatively disposed notches 31 and 32, the latter 100

being smaller than the former and through the tube extends a fuse wire 33. Clamps 34 on the upper ends of the tube 30 pivotally mount latches 35 which engage catches 36 mounted on the outer surface of the panel 6 by means of a plate 37 and fastening elements 38.

The upper end of the fuse wire holds the latch wire 35 in the position shown in Figure 2 by being extended over hook 39 on the panel and engaged with terminal bolt 40.

The terminal bolts 40 hold a plate 41 on the top of the outer surface of the panel 6 and a hood 42 is engaged therewith and also with the plate 37 and extends over the fuses to protect the same from the weather.

The lower ends of the tubes are mounted in clamps 43 formed on the outer ends of L-shaped rockers 44 which are pivotally mounted as at 45 in bearings 46 connected to knife switch elements 47 fastened by suitable means on the bottom inside of the panel 6.

The lower ends of the fuse wires 33 are connected with terminal bolts 49 on the rockers 44. The left hand and center rockers have lateral arms 50 for engaging in notches 51 formed at the lower ends of the slides 12 for holding these slides in their normally raised positions as shown in Figure 3.

A pair of switch blades 53 are pivotally mounted as at 54 and normally held in raised positions by springs 55. These blades 53 are adapted to be swung down into engagement with elements 47.

The electric circuit is connected to the apparatus by means of terminal 57 on a plate 58 mounted in the top of the casing and with which the hood 42 engages when the panel is closed and with a terminal 59 connected by suitable conducting means 60 with the left hand rocker 44.

It will therefore be seen that the current will flow through the left hand fuse when all parts are initially set up. If the fuse wire in the left hand tube burns out then the left hand latch 35 is free to rock so that this left tube will gravitate downwardly, rocking the rocker 44.

The rocking of this left hand rocker 44 disengages its arm 50 from the left hand slide 12 so that the same will gravitate downwardly slow enough to give an opportunity of unloading the circuit and when the block 14 engages the left hand switch blade 53 it will contact the same with the switch element 47 so that the circuit will be closed through the center fuse.

Should the center fuse burn out of course, this would cause the releasing of the other slide 12 and the closing of the other switch as will be quite apparent without a more detail description thereof.

We consider that the main utility of this invention resides in power circuits extending over great distances wherein it is necessary to

go out in the country for a considerable distance to renew a fuse. Obviously with fuse apparatuses as disclosed herein a regular inspection could be made at intervals and thus practically eliminating the necessity of long trips to renew fuses in emergencies.

It is thought that the construction, operation, utility and advantages of this invention will now be quite apparent to those skilled in this art without a more detailed description thereof.

The present embodiment of the invention has been disclosed in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described our invention, what we claim as new is:

1. In an apparatus of the class described, a casing, a panel hingedly mounted in the casing, a plurality of fuses, supporting means on the panel for the fuses, means for automatically placing the fuses in a circuit one after the other as they burn out, and an escapement mechanism mounted on said panel for controlling said means to provide a predetermined time interval between the burning out of one fuse and the setting of the next fuse in the circuit.

2. An apparatus of the class described comprising a casing, a panel hingedly mounted in the casing, slides mounted on the panel, escapement mechanism cooperatively connected with the slides, switches adapted to be closed by the slides, fuses, supporting means on the panel for the fuses, means controlled by the fuses for normally retaining the slides against movement relative to the panel, one of said fuses being in circuit and when burned out adapted to release one of the slides for closing a switch for placing the next fuse in the circuit.

In testimony whereof we affix our signatures.

EDWARD H. BOICOURT.
ALLAN H. BOICOURT.
